FRANCIS H. BROWN, OF STAMFORD, CONNECTICUT.

Letters Patent No. 74,294, dated February 11, 1868.

IMPROVEMENT IN NECK-TIE HOLDERS.

The Schedule referred to in these Letters Patent and making part of the same.

TO ALL WHOM IT MAY CONCERN:

Be it known that I, FRANCIS H. BROWN, of Stamford, in the county of Fairfield, and State of Connecticut, have invented a new and improved Cravat-Holder; and I do hereby declare that the following is a full, clear, and exact description thereof, which will enable others skilled in the art to make and use the same, reference being had to the accompanying drawings, forming part of this specification.

Figures 1, 2, and 3 represent side views of my improved cravat-holder, showing various modifications of the same.

Figure 4 is a perspective view of the same.

Similar letters of reference indicate corresponding parts.

This invention relates to a new device for holding down neck-ties and cravats on gentlemen's standing collars, its object being to prevent the cravat from slipping over the upper edge of the collar.

It has heretofore been a great inconvenience, that neck-ties and cravats could not be prevented from slipping off standing collars, and from thus becoming disarranged, unless they were pinned to the collars, whereby the cravats as well as the collars were injured.

My invention consists in the use of a metallic hook, which is either provided with a button, or which can be secured to a button, so that it can be attached to the button at the back of the neck-band of the shirt, or fitted in the button-hole provided in the said neck-band. The hook fits over the cravat, and effectually prevents it from slipping off the collar.

A represents a hook, made of sheet metal, wire, or any other suitable material. The inner arm *a* of this hook is either provided with a stud, *b*, as in fig. 1, whereby the device can be fitted in the button-hole arranged through the back of the neck-band *c* of the shirt, and through the standing collar *B*, or through the latter only, if desired; or the arm *a* is slotted, as in figs. 2 and 3, so that it can be fitted to a stud, *e*, arranged through the aforesaid button-holes, as in fig. 3, or to a button, *f*, arranged in place of the button-hole on the neck-band *c*, as in fig. 2, or on the collar. In case the stud is not secured to the hook, the back arm *a* of the hook should be split, as in fig. 4, so as to form one or more recesses, into which the shank of the stud *e* or button *f* is fitted. The upper and lower ends of such recesses are closed by the natural spring of the two parts of the arm *a*, as will be easily understood from fig. 4.

By arranging two or more such recesses, the device can be set higher or lower on the collar, as may be desired. When the hook *A* is thus secured to the neck-band and collar, the cravat *g* is fitted between the inner arm *a* and the outer arm *b* of the hook, and its upper edge thus strikes against the junction of the arms of the hook, and it is thus prevented from slipping off over the upper edge of the collar. Instead of arranging this hook at the back of the neck-band, it may be arranged at the side, or two or more may be applied at once, as may be desired. The hook *A* may also be used for attaching cravats to front shirt-buttons.

I claim as new, and desire to secure by Letters Patent—

As a new article of manufacture, a gentleman's neck-tie holder *A*, constructed substantially as described, and so arranged that it can be attached to the neck-band or collar of the shirt, either by means of a button secured to the hook itself, or forming the hook without a button, and attaching it to a stud or button affixed to the collar or neck-band of the shirt, or to the removable collar, as herein shown and described.

FRANCIS H. BROWN.
